We claim the ornamental design for 3D glasses, as shown and described.

DESCRIPTION

[This application claims priority to U.S. design patent application Ser. No. 29/326,498, filed on Oct. 20, 2008, the disclosures of which are incorporated herein by references.]

The file of this patent contains at least one drawing executed in color. Copies of this patent with color drawing(s) will be provided by the Office upon request and payment of the necessary fee.

FIG. 1 is [an isometric] a perspective view of the front and top of the 3D glasses showing the design of our invention; FIG. 2 is a front elevation view of the 3D glasses;

FIG. 3 is a rear elevation view [showing exterior of temple of the 3D glasses of FIG. 1] of the 3D glasses of FIG. 1, wherein the exterior of the temples are shown;

FIG. 4 is a side [perspective] elevation view of the 3D glasses of FIG. 1;

FIG. 5 is a top [front elevation] plan view of the 3D glasses of FIG. 1; and,

FIG. 6 is a bottom [elevation] plan view of the 3D glasses of FIG. 1.
